FENDER ORNAMENT FOR AUTOMOBILES OR THE LIKE

Eugene Bordinat, Jr., Bloomfield Hills, Mich., assignor to
Ford Motor Company, Dearborn, Mich., a corporation
of Delaware

Filed Oct. 13, 1961, Ser. No. 67,067

Term of patent 7 years

(Cl. D14—6)

FIGURE 1 is a side elevational view of a fender ornament for automobiles or the like, showing my new design;

FIGURE 2 is a top plan view;

FIGURE 3 is a front view;

FIGURE 4 is a rear view;

FIGURE 5 is a sectional view taken on the plane indicated by the line 5-5 of FIGURE 1;

FIGURE 6 is a sectional view taken on the plane indicated by the line 6-6 of FIGURE 2; and

FIGURE 7 is a sectional view taken on the plane indicated by the line 7-7 of FIGURE 1.

I claim:

The ornamental design for a fender ornament for automobiles or the like, substantially as shown.
